UNITED STATES PATENT OFFICE.

AUGUST GSCHWEND AND RAYMOND G. CUMBER, OF SEATTLE, WASHINGTON; SAID GSCHWEND
ASSIGNOR TO ADELBERT F. HAMMER, OF SEATTLE, WASHINGTON.

SKIRT-MARKER.

No. 900,849.

Specification of Letters Patent.

Patented Oct. 13, 1908.

Application filed November 8, 1907 Serial No. 401,347.

To all whom it may concern:

Be it known that we, AUGUST GSCHWEND and RAYMOND G. CUMBER, both citizens of the United States of America, and residents 5 of the city of Seattle, in the county of King and State of Washington, have invented certain new and useful Improvements in Skirt-Markers, of which the following is a specification.

10 Our invention has for its primary object, to provide an efficient device of the above character which can be readily operated to produce marks on a skirt to indicate the proper length thereof.

15 A further object resides in the provision of a comparatively simple construction, the discharge head of which can be adjusted vertically.

20 A further object of our invention is to provide a device of this character, which can be operated by the person wearing the skirt to be marked.

25 With the above and other objects in view, to be referred to as the description progresses, our invention resides in the structural features, arrangements and combinations of parts hereinafter described and succinctly defined in the appended claims.

30 Referring now to the accompanying drawing, in which like numerals of reference indicate like parts throughout the several views: Figure 1 is a view in side elevation of our invention, illustrating the same in operation. Fig. 2 is a detail, fragmentary sectional view, 35 on enlarged scale, of the upper portion of the device, and Fig. 3 is a view in perspective of the discharge head of the device.

35 In carrying out our invention, we provide a suitable stand or upright 1, on which the discharge head 3, is supported for vertical adjustment, said stand or upright having a supporting base 2. Head 3, as now considered, is carried on the lower end portion of a pipe 4, through which the marking material 45 travels from a suitable source of supply, as will be more fully described hereinafter. The lower end portion of tube or pipe 4 is bent or curved outwardly from stand 1 so as to support head 3 in a substantially horizontal plane, as clearly illustrated in Fig. 1.

50 Tube or pipe 4 is adjustably supported on stand 1 by suitable couplings, as 5, provided with thumb screws 6. By this construction it will be observed that the couplings can 55 also be raised or lowered, thereby enabling

the obtaining of the proper spacing thereof to insure of pipe 4 being firmly held to stand 1 while head 3 is supported at various elevations above the floor.

The marking material now employed is in powdered form, and this in operation is placed in a supply receptacle or chamber 7, from which it falls into pipe 4 by gravity. Air under pressure is admitted into pipe 4 to discharge the marking material through the 60 apertures 3' of head 3. The apertures 3' of head 3 are arranged in horizontal alinement so as to direct the marking material in such a manner that the latter will produce a horizontal line composed of dots or dashes, on the 65 skirt. Air as now considered, is supplied to pipe 4 through the medium of a bulb 8, said bulb being secured to a pipe 9 which is connected by a coupling 10 to pipe 4. Supply receptacle or chamber 7 has a funnel shaped 70 lower portion provided with a nipple 7' which is threaded in the upper end portion of a vertical conduit 10' of said coupling, and pipe 4 is threaded in the lower end portion of said conduit 10'. Pipe 9 is threaded in an 75 inclined conduit which communicates with conduit 10' at a point between pipe 4 and nipple 7', as clearly shown in Fig. 2. To prevent the marking material from falling into pipe 4 in a continuous manner and in too 80 great a quantity, we place in receptacle or chamber 7 a perforated wall 11, through which said material must pass in falling to pipe 4. Perforated wall 11, as now considered, forms an end wall of a removable can 85 12, which, as for example, may be the can in which the marking material is sold on the market. Pipe 9 is preferably curved so that its free end will lie on the same side of stand 1 as head 3. By this construction said pipe 90 12 can be used as a handle to lift and move the device, when desired. Further, it will be observed that bulb 8 will be in such position that it can be readily grasped and operated by the person wearing the skirt to be marked.

To insure of a charge of the material falling from the supply chamber into pipe 4, the device must be jarred a little, and when the device is moved around the skirt in marking the same, the jar incident to the lifting and replacing of the device on the floor is sufficient.

By our improved device plaited or fancy skirts as well as plain ones can be marked in an equally efficient manner, and the line of 110

marks will be clear and distinct for the entire distance around the skirt, for head 3 does not come in contact with the goods, and consequently there is no danger of the goods of the skirt being moved by the device during the marking operation.

By adjusting pipe 4 vertically, the head 3 can be raised or lowered, as desired, for marking the skirt at any desired distance above 10 the floor.

Having thus described our invention, what we claim as new, and desire to secure by Letters Patent of the United States of America, is:

1. A device of the character described comprising a stand, a vertically disposed pipe supported thereon for vertical adjustment, a horizontally disposed head on the lower portion of said pipe for discharging the marking material, a coupling secured to the 15 upper end of said pipe, said coupling being formed with a vertical conduit and an inclined conduit communicating with said first named conduit intermediate its ends, a supply receptacle arranged above said coupling and 20 having a nipple depending from its lower portion, said nipple being secured in the upper portion of the vertical conduit of said coupling, a pipe communicating with the inclined conduit of said coupling and extending upwardly over said receptacle, and a bulb on 25 30

said last named pipe arranged on the same side of said stand as said horizontally disposed head.

2. A device of the character described comprising a stand, a vertically disposed pipe having a horizontally disposed head on its lower portion, couplings slidably engaged on said stand and on said pipe, set screws in said couplings engaged with said stand and with said pipe, a coupling secured on the upper end of said pipe, said coupling being formed with a vertical conduit and an inclined conduit communicating with said first named conduit intermediate its ends, a supply receptacle arranged above said coupling and having a funnel shaped bottom portion provided with a nipple secured in the upper end of the vertical conduit of said coupling, a pipe communicating with the inclined conduit of said coupling and extending upwardly to form a handle, and a bulb on the upper end of said last named pipe.

Signed at Seattle, Washington this 31st day of October 1907.

AUGUST GSCHWEND.
RAYMOND G. CUMBER.
